US0D1014456S

(12) **United States Design Patent** (10) **Patent No.:** **US D1,014,456 S**
(45) **Date of Patent:** **** Feb. 13, 2024**

(54) **SPEAKER COVERS OF HEADPHONES**

(71) Applicant: **SHENZHEN SHOKZ CO., LTD.**,
Guangdong (CN)

(72) Inventors: **Lei Zhong**, Shenzhen (CN); **Zhi Cai**,
Shenzhen (CN); **Sunjie Huang**,
Shenzhen (CN); **Zeteng Yan**, Shenzhen
(CN); **Qian Chen**, Shenzhen (CN);
Piyou Cheng, Shenzhen (CN);
Yueqiang Wang, Shenzhen (CN)

(73) Assignee: **SHENZHEN SHOKZ CO., LTD.**,
Shenzhen (CN)

(**) Term: **15 Years**

(21) Appl. No.: **29/792,743**

(22) Filed: **Apr. 21, 2022**

(30) **Foreign Application Priority Data**

Oct. 22, 2021 (CN) 202130694639.5

(51) **LOC (14) Cl.** **14-01**

(52) **U.S. Cl.**

USPC **D14/205**; D14/217

(57) **CLAIM**

The ornamental design for speaker covers of headphones, as shown and described.

DESCRIPTION

FIG. 1 is a right perspective view of speaker covers of headphones showing our new design;

FIG. 2 is a left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design while all other broken lines depict portions of the speaker covers of headphones that form no part of the claimed design; all broken lines form no part of the claimed design.

1 Claim, 8 Drawing Sheets
